UNITED STATES PATENT OFFICE.

JOHN S. HUFFMAN, OF ROCKFORD, ILLINOIS.

BOTTLE-STOPPER.

No. 815,172.

Specification of Letters Patent.

Patented March 18, 1906.

Application filed July 29, 1905. Serial No. 271,867.

To all whom it may concern:

Be it known that I, JOHN S. HUFFMAN, a citizen of the United States of America, residing at Rockford, in the county of Winnebago and State of Illinois, have invented certain new and useful Improvements in Bottle-Stoppers; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

Figure 1 is a central vertical section of a bottle provided with my improvements. Fig. 2 is a top plan view of the same complete. Fig. 3 is an isometrical detail view of the bottle-closure.

15 A is a bottle having a transversely-enlarged circular recess A' in the neck A² thereof, terminating at its lower end in a circular closure-seat A³ and at its upper end in a spiral convolution A⁴.

20 B is a circular closure fitted to the seat A³ in the neck A² of the bottle to hermetically seal the same.

25 C is a spiral spring connected by its lower end and preferably through the metallic cap C' to the closure B and terminating at its upper end in a ring C², whereby to turn the same under the convolution A⁴ at the upper end of the circular recess A' in the neck A² of the bottle, the spiral spring being includible and compressible between such closure and convolution.

30 The closure may be removed from the bottle by rotating it from left to right by means of the ring C² and may be applied thereto by 40 rotating the same in the opposite direction.

35 This closure requires no other agency except its spring to secure it hermetically upon its seat in the neck of the bottle. It can be withdrawn from or applied to the neck of the 45 bottle to open or close the same without the employment of a corkscrew or other utensil of any description. The bottle and closure may be easily manufactured at a very moderate cost.

Obviously the above-described bottle could not be hermetically sealed by any closure except one substantially like the one described in connection therewith herein.

Having fully described my invention, what I claim as new, and desire to secure by Letters Patent, is—

1. In a bottle-stopper, in combination, a bottle having a transversely-enlarged circular recess, in the neck thereof, terminating, at its lower end, in a circular closure-seat and, at its upper end, in a spiral convolution, a circular closure fitted to the seat in the neck of the bottle, to hermetically seal the same, and a spiral spring includible and compressible between the closure and convolution at the upper end of the transversely-enlarged circular recess in the neck of the bottle, substantially as described.

2. In a bottle-stopper, in combination, a bottle having a transversely-enlarged circular recess, in the neck thereof, terminating, at its lower end, in a circular closure-seat and, at its upper end, in a spiral convolution, a circular closure fitted to the seat in the neck of the bottle, to hermetically seal the same, and a spiral spring connected, by its lower end, to the closure and terminating, at its upper end, in a ring, whereby to turn the same under the convolution at the upper end of the transversely-enlarged circular recess in the neck of the bottle, to secure the closure upon its seat, substantially as described.

3. In a bottle-stopper, in combination, a bottle having a circular recess A' in the neck thereof, terminating, at its lower end, in a circular closure-seat A³ and, at its upper end, in a spiral convolution A⁴, a closure fitted to the seat A³, and a spiral spring C connected, by its lower end, to the closure B and terminating, at its upper end, in means whereby to turn the same, substantially as described.

In testimony whereof I have signed my name to this specification in the presence of two subscribing witnesses.

JOHN S. HUFFMAN.
